(57) **CLAIM**

The ornamental design for a display screen with graphical user interface, as shown and described.

DESCRIPTION

1. Display screen with graphical user interface

FIG. 1.1: Horizontal view

FIG. 1.2: Vertical view

FIG. 1.1 is a front view of a first image in a sequence for a display screen with graphical user interface; and FIG. 1.2 is a second image thereof.

The outermost broken line rectangle shows the display screen, and forms no part of the claimed design. All other broken lines show portions of the graphical user interface that form no part of the claimed design.

The appearance of the transitional image sequentially transitions between the images shown in Reproductions FIG. 1.1 and FIG. 1.2. The process or period in which one image transitions to another image forms no part of the claimed design.
